UNITED STATES PATENT OFFICE

KENNETH S. WAGONER, OF OAK PARK, ILLINOIS, ASSIGNOR TO ELECTRICAL ENGINEERS EQUIPMENT CO., OF MELROSE PARK, ILLINOIS, A CORPORATION OF ILLINOIS

DISCONNECT SWITCH

Application filed August 17, 1929. Serial No. 386,693.

This invention relates to electric switches and more particularly to stops, especially friction stops, for switches. While this invention is especially concerned with disconnect switches such as are used in high voltage systems, it is not limited thereto, being also of general application.

It is one of the objects of the present invention to provide a switch with a friction stop for preventing a gradual accidental closure of the switch when the same is left open for prolonged periods of time. The stop exerts sufficient pressure to keep the blade in its open position unless it is moved to the closed position by an operator.

It is a further object of the present invention to provide a friction stop which may be built as a unit and applied to switches already in service with a minimum amount of labor and which will require no machining, cutting or drilling into the switches.

The only labor that is required in applying my stop to switches already in service is that necessary to first remove the switch blades place the stop in position, and then replace the blades.

It is a further object of the present invention to provide a stop which is applicable to back connected disconnect switches as well as to front connected switches.

The attainment of the above and further objects of the present invention will be apparent from the accompanying specification taken in conjunction with the drawings forming a part thereof.

In the drawings:

Figure 1 is a side elevational view of a double throw switch, illustrating the application of the principles of my invention thereto;

Figure 2 is a top view of the pivotal support for the switch blades;

Figure 3 is a fragmentary side elevation showing the central insulator of the switch and the manner of mounting the blade thereon;

Figure 4 is an end view of the pivotal blade support and friction stop for the blade;

Figure 5 is a view of the base plate for the friction stop; and

Figure 6 is a view of the stop plate for the friction stop.

Referring now more particularly to Figure 1 of the drawings, I have shown my invention as applied to a conventional double throw switch. It is, of course, understood that the invention is equally applicable to single throw switches and is also applicable to disconnect switches of different types. In the switch shown in Figure 1, the grounded base plate 1 may be of any preferred construction and supports three insulators indicated at 2, 3 and 4. The insulator 2 supports a terminal clip 5 for receiving a line conductor 6 and a contact member 7, which is adapted to be contacted with by a blade 8 mounted, in a manner to be more fully set forth as the description proceeds, upon the insulator 3. In a like manner the insulator 4 is provided with a line terminal clip 9 for receiving a line conductor 10 and with a terminal 11 also adapted to be engaged by the switch blade 8, said terminal 11 being engaged by the switch blade when the blade is swung to a position opposite that shown in the drawings.

Reference may now be had more particularly to Figures 2, 3 and 4, showing the manner in which the switch blade 8 is supported upon the insulator 3, and also showing the novel friction stop for the switch. The central insulator 3 is provided with an insulator cap 15 which is suitably secured to the top of the insulator.

A substantially U-shaped switch clip 16 comprising two clip portions 17 and 18 joined together by a connecting portion 19 is suitably secured to the insulator cap 15 in any desired manner. The switch blade 8 comprises a number of blade sections 25, 26, 27 and 28 pivotally mounted on the clip 16. The blade sections 25 and 26 are pivoted to the clip portion 17 whereas the blade sections 27 and 28 are pivoted to the clip portion 18. The two blade members 25 and 26 embrace the opposite sides of the clip portion 17, being pivoted thereto by means of a bolt indicated at 30 and being held in firm contact with the clip portion 17 as by a pair of spring washers 31.

and 32. The blade members 27 and 28 are similarly mounted.

- The friction stop for the switch blades comprises a base plate 35, of a shape such as is shown more particularly in Figure 5, a stop plate 36 of a shape such as is shown more particularly in Figure 6, and a pair of guiding studs 37 and 38 which are embraced by compression springs 39 and 40, respectively.
- 10 The plate 35 has notches 45 projecting from each end thereof, the notches 45 embracing a portion of the switch clip members 17 and 18, respectively, for holding the base plate against movement crosswise of the switch clip.
- 15 The base plate has a pair of tapped holes 46 formed therein for receiving the guide studs 37 and 38, those studs being threaded into the holes 46. The stop plate 36 has a number of holes 49-49 formed therein. The top portion 20 of the studs 37 and 38 pass freely through the holes 49-49, the stop plate being supported by the springs 39-40.
- When the switch blade 8 is in the position shown in Figure 3, the surface 50 of the blade 25 and the corresponding surface of the blade 27 bear against the stop plate 36 pressing it downward, thereby compressing the springs 39 and 40. During the switch opening movement of the blade 8 the stop plate 36 is first 30 pushed downward, thereby further compressing the springs 39 and 40 and as the blade approaches a position at right angles to the position shown in Figure 3, it permits the plate 36 to move slightly away from the plate 35 under the action of the springs 39 and 40 until the plate is again in substantially the 35 position shown in the drawings. At this time the planar surface or edge 51 of the blade member 26 and the corresponding edge 40 of the blade member 27 are in engagement with the stop plate 36. It is to be noted that the stop plate, acting under the force of the 45 springs 39 and 40, tends to bias the switch blade to the open position when the blade is in the vicinity of the full open position, and it tends to bias the blade to the closed position when the blade is in the vicinity of the closed position. This is true whether the blade is in the vicinity of the contact 7 or 50 within the vicinity of the contact 11. The switch blade 8 is beveled at the corners where the side 50 would normally meet the edge 51, as may be seen in Figure 3. As may be seen in this figure, the beveled corners present substantially flat surfaces to the top plate 36 whereby the blade 8 may be left in an open position intermediate its full closed and open positions, and be retained in that position by the plate 36, should this be necessary. If the 55 friction stop member is applied to a single throw switch instead of to a double throw switch, as shown in Figure 1, that is, to a switch wherein the insulator such as the insulator 9 with its associated contact 11 is removed, the action would be identical.

It is apparent from the above description that I have provided a friction stop for electric switches which is simple in construction and requires but few parts to accomplish the desired results. In view of the fact that the base plate 35 is not bolted or otherwise rigidly secured to the switch construction it is quite a simple matter to install my friction stop upon switches already constructed since no additional machining of the switch parts is necessary. This is a decided advantage since these friction stops can be built up as individual units and can be applied to switches already in service with a minimum amount of labor, the only labor required being that necessary to remove the switch blades, place the stop between the fingers of the switch clip, and then replace the blades.

While the switch herein shown is a front connected switch, that is one wherein the terminal connections such as 5 and 9 are brought in from the front of the base plate 1, it is apparent that the present invention is equally applicable to back connected switches, that is, to switches wherein the connections extend from the switch clips through the insulators to the back of the base plate 1.

In compliance with the requirements of the patent statutes I have herein shown and described a preferred embodiment of my invention. It is, however, to be understood that the invention is not limited to the precise construction herein shown, the same being merely illustrative of the invention. What I consider new and desire to secure by Letters Patent is:

1. In combination, a pair of spaced parallel switch clips, switch blade members pivoted on the clips, a base plate resting between the clips and movable with respect thereto, a stop plate between the base plate and the switch blades, a guiding stud mounted on the base plate and extending through an opening in the stop plate, and spring means between the two plates for pressing the stop plate against the blade to act as a friction stop for the blade, said base plate and said stop plate being free of mechanical fastenings to the switch and both plates being slideable along the switch clip, both of said plates being free of portions encircling the clips.

2. An electric switch including a pair of switch clips, permanently parallel connected switch blades pivotally mounted on the clips, and an expandible unit comprising two plates and spring means urging the plates apart, said unit being inserted between the switch clips and compressed by the blades in their movement, whereby the unit acts as a brake for the switch blades, both of said plates being free of mechanical fastening to the switch and both being slideable along the switch clips.

3. In combination a switch blade, a pivotal support for the same, said blade having

planar edges extending lengthwise and cross-wise of the blade at the supported end thereof, a plate movable along the support and bearing along one of those edges when the
5 switch is fully closed and along the other edge when the switch is open, spring means for urging the plate against the edges, and a base plate slidable with respect to the pivotal support and held against sliding movement along the support solely by the spring means, said base plate providing a bearing surface for the spring means.
10

In witness whereof, I hereunto subscribe my name this 12th day of August, A. D. 1929.
15 KENNETH S. WAGONER.
